CLAIM

The ornamental design for a blister package, as shown and described.

DESCRIPTION

FIG. 1 is a front perspective view of a first embodiment of my design for a blister package;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side view thereof (the left side is a mirror image thereof);

FIG. 7 is a front perspective view of a second embodiment of the blister package;

FIG. 8 is a front elevational view of the second embodiment;

FIG. 9 is a top plan view of the second embodiment; and,

FIG. 10 is a right side view of the second embodiment (the left side is a mirror image thereof).

The broken lines shown on the drawings represent environmental structure and form no part of the claimed design.
